tion of Ohio

Application August 6, 1948, Serial No. 42,816

21 Claims. (Cl. 101—119)

1

This invention relates to cylindrical printing surfaces and, more particularly, to improved printing cylinders which may be employed to effect printing in accordance with orthodox methods, such as relief, gravure, offset, gelatin, or the like, as well as with the newer methods of printing and/or coating, such as those known as electronographic or migratetic methods. The invention also relates to methods of constructing the improved cylinders.

This application discloses and claims subject matter which is disclosed, in part, but not claimed in my copending application Serial No. 24,232, filed April 30, 1948, entitled "Electrographic Reproduction Processes."

In conventional rotary relief printing presses, the cylinders are usually constructed of heavy castings. To these cylinders are secured separate plates corresponding to an entire page of the magazine, newspaper, or the like which is to be printed and as many plates are used as can be economically and practically arranged on the periphery of the cylinder. For finer quality work electrotype plates are made from the original photo-engraved plates and these electrotype plates are then curved, backed by lead, and fastened in place on the cylinder. In newspaper printing, stereotypes are made from paper molds which are prepared from the original photoengraved plates or metal type forms and these stereotypes are then secured to the printing cylinders.

In preparing the plates for relief printing, it has been necessary heretofore to rout the photoengraved plates from which the electrotypes or stereotypes are prepared so that the non-printing areas will be deep enough to prevent the ink rollers from inking these blank areas. This is a costly and time-consuming operation. In addition, orthodox relief presses require that the separate curved plates have their inking and printing surfaces exactly cylindrical. The effecting of this latter operation is known as "making ready" and is generally performed by raising low spots or areas with packing to insure uniform inking of the work or printing areas and also to withstand the necessary pressure to effect ink transfer to the material being printed. Other conventional methods of printing likewise require extensive and costly preparation of the printing areas for the cylinders.

An object of this invention is the provision of novel printing cylinders and methods of making the same which eliminate the need for routing of plates, the preparation of separate electrotype or stereotypes, and the need for make-

2

ready, the novel cylinders being especially adapted for use in presses that print with little or no pressure, such as electronographic presses and the cylinders being also capable of employment in orthodox presses where pressure is utilized.

Another object of the invention is the provision of novel cylindrical printing or coating cylinders and methods of making the same whereby the cylinders are relatively light in weight and inexpensive to construct and which produce improved quality printing or coating at reduced cost.

A further object of the invention is to provide an improved printing cylinder and method of constructing the same in which the entire form comprising the separate pages or work areas to be printed are produced directly upon the surface of the cylinder without the need of preparation of separate plates, electrotypes, and/or stereotypes.

A still further object of the invention is to provide an improved printing cylinder and method of constructing the same such that the periphery of the cylinder is provided with a novel perforate surface upon which the printing and non-printing areas may be directly formed by photographic and/or electroplating procedures.

An additional object of the invention is to provide an improved printing cylinder and method of making the same as defined in the preceding object and in which fluid may be supplied to portions of the surface of the cylinder from the interior thereof at a controlled rate and uniformly distributed to the entire surface of the cylinder.

A more specific object of the invention is the provision of an improved printing cylinder and method of making the same wherein the cylinder comprises a perforate shell on which a strip or wire-like member, having protuberances therealong is helically wound with the protuberances on the portion of the strip or wire forming one turn of the helix engaging the planar surfaces of the strip or wire in the next turn of the helix to thereby provide staggered, elongated, narrow passageways for fluid, the printing and/or non-printing areas being directly formed on the outer surface of the helix.

A still further object of the invention is the provision of an improved cylinder and method of making the same as defined in the preceding object such that the cylinder may be employed for applying a uniform coating upon strip material when the entire surface of said helix is left in uncovered condition.

55 The invention further resides in certain novel

steps of procedure, features of construction, and combinations and arrangements of parts, and further objects and advantages thereof will be apparent to those skilled in the art to which it pertains from the following description of the present preferred embodiment, and certain modifications, described with respect to the accompanying drawings in which similar reference characters represent corresponding parts in the several views, and in which:

Fig. 1 is a longitudinal sectional view through a printing cylinder constructed in accordance with this invention, the support for one end of the cylinder being removed and a portion intermediate the ends of the cylinder being broken away to reduce the length of the figure;

Fig. 2 is a greatly enlarged, fragmentary view of a section of the side wall of the printing cylinder and of the valve and inner shell associated therewith, the view being taken substantially between the lines A—A' and B—B' of Fig. 1;

Fig. 3 is a greatly enlarged, fragmentary sectional view of the upper right-hand portion of the cylinder illustrated in Fig. 1;

Fig. 4 is an enlarged, fragmentary, end elevational view of a portion of the cylinder, the view being taken from the right-hand side of Fig. 3 and showing a means for effecting adjustment of the valve for controlling flow of fluid through the side wall of the cylinder;

Fig. 5 is a fragmentary, sectional view similar to Fig. 3 but with the end wall and the helical covering for the cylinder omitted, the figure illustrating a modification of the construction shown in Fig. 3;

Fig. 6 is a greatly enlarged, fragmentary, plan view of a portion of the periphery of the cylinder illustrated in Fig. 1 before the printing and non-printing surfaces have been formed thereon, the view being taken approximately as indicated in 6—6 in Fig. 1 and a portion of a helically arranged wire or strip being broken away to reveal the surface of the cylindrical shell thereunder.

Fig. 7 is a fragmentary, detached, perspective view to a greatly enlarged scale of a portion of the strip or wire which is to be helically wound upon the cylinder;

Fig. 8 is a fragmentary, detached, plan view to a greatly enlarged scale of a portion of the periphery of the completed cylinder illustrating a printing surface formed thereon adapted to receive ink from inking rolls, the non-printing surfaces being shown intermediate the printing surfaces, which non-printing surfaces do not take ink from the printing rolls;

Fig. 9 is a view similar to Fig. 8, but showing the printing and non-printing surfaces reversed, whereby the cylinder may be employed for printing the same pattern as that produced by the cylinder of Fig. 8 by supplying printing fluid from the interior of the cylinder rather than exteriorly by means of inking rolls;

Fig. 10 is a fragmentary, detached sectional view to a greatly enlarged scale illustrating a step in the procedure for constructing printing cylinders in accordance with this invention; and,

Fig. 11 is a fragmentary, detached, perspective view to a greatly enlarged scale of a modification of the strip material which is wound upon the cylinder.

A printing cylinder, constructed in accordance with this invention, has been illustrated in the drawings in the form which is especially adapted for use in printing methods employing light or no pressure, for example, such as those known

as offset, or electronographic. It will be understood, however, that the construction of the printing cylinder and the method of producing the same, as hereinafter described, is the same when forming cylinders suitable for use in relief or other orthodox methods of printing, the only difference being that the cylindrical shells and other operating parts must have their dimensions sufficiently increased to withstand the pressures of the press.

The printing cylinder, embodying the invention as illustrated in the drawings, and generally designated 10, comprises a cylindrical shell 11 which is provided with a plurality of openings or ports 12 of relatively small diameter at spaced points about its periphery, these openings being interconnected, on the outer surface of the shell, by longitudinally extending grooves, such as 13, see Figs. 2, 3, and 6. One end of this shell is removably supported upon an end plate or member 14, which, when the cylinder is employed for electronographic printing, is formed of electrical insulating material. If, however, the cylinder be employed for relief or other orthodox methods of printing, the member 14 may be formed of metal. Between the shell 11 and the member 14 is interposed a suitable packing 15 to prevent the flow of fluid therebetween.

Connected with the end plate or member 14 is an annular member 16 which constitutes a bearing support for the end of the cylinder. More specifically, the central opening of the member 16 is counterbored and has the outer race of an anti-friction bearing 17 mounted therein, the inner race of the bearing being supported upon a non-rotatable tubular member 18 adjacent the inner end of the latter. The tubular member 18 is slidably supported, intermediate its ends, in a suitable sleeve 19 which is adjustably carried by frame members 20 and 21. Thus, the sleeve 19 is provided, adjacent its ends, with outwardly extending circular flanges 22 and 23 which overlie the outer surfaces of the frame members 20 and 21 respectively, and are suitably secured thereto in a manner such that the sleeve 19 and tubular member 18 may be adjusted within the frame members to bring the cylinder 10 into the desired spaced relationship in the press.

The diameter of the tubular member 18 is reduced adjacent its outer end and the external surface of this reduced portion is provided with a screw thread cooperating with a nut member 24. The nut 24 is rotatably supported but prevented from longitudinal movement by virtue of being provided with an outwardly extending flange portion 25 which is received within the annular recess of an internally shouldered member 26 which is secured to the flange 23. Surrounding a portion of the nut 24 is an actuating member 27 which is secured to the nut for effecting rotation thereof by means of screws 28, the member 27 being provided with radially extending bores 29 in which a bar or the like may be inserted for effecting turning thereof. It will be readily apparent that rotation of the member 27 and hence of the nut 24 causes the tubular member 18 to move longitudinally relative to the sleeve 19 and the frame members 20 and 21 thus enabling the parts of the cylinder 10 to be assembled and disassembled so as to facilitate cleaning thereof.

The end plate or member 14 is also provided with a centrally located axial bore or opening 30 which extends coaxially with and in communication with the bore 31 through the tubular mem-

ber 18. The adjacent surfaces of the member 14 and the tubular member 18, adjacent the cooperating bores or passageways 30 and 31, are provided with cooperating packings 32 and 33 to prevent the leakage of liquid at this point.

The other end of the tubular shell 11 is supported upon an annular member 34 and a packing 34a is placed therebetween to prevent the escape of liquid. The member 34 will be of insulating material if the cylinder be employed for electronographic printing, but may be formed of metal when the cylinder is employed for printing by more orthodox methods. The member 34 is in turn connected with an annular member 35 which is connected to an end member 36, the latter being provided on its outer face with a gear 37. This gear cooperates with a driving gear, not shown, to effect rotation of the cylinder and, if desired, a gear similar to 37 may be provided adjacent the other end of the cylinder, as for example, on the member 16.

Within the annular member 34 is disposed a disk 38 which is connected to the member 36, the latter and disk 38, as well as the gear 37 having aligned central openings through which a non-rotatable tubular shaft 39 extends coaxially of the cylinder and in alignment with the tubular member 18. The member 36 and the tubular shaft 39 may be provided with a suitable anti-friction bearing therebetween similar to that indicated at 17, and the shaft 39 has its outer end suitably supported in a framework, not shown. Preferably the portion of the tubular member or shaft 39 inside the cylinder is provided on its exterior with an electrical insulating sleeve or bushing 39a when the cylinder is to be employed for electronographic printing so that one of the elements of the electrical field producing members may be supported thereon.

The inner end of the tubular member 39 is received in a cylindrical recess in a disk 40 and the outer side surface of the latter is provided with a cylindrical boss 41 which is received in a cylindrical groove in the adjacent face of the member 14. The cylindrical boss 41 is provided, intermediate the disk 40 and the member 14, with a plurality of openings, such as 42, to provide communication from the bore 31, through the bore 30, and through the cylindrical boss 41 to the exterior thereof, for a purpose hereinafter described. The disk 40 and the annular member 34 support the ends of an inner imperforate cylindrical shell 43 in spaced relation with the shell 11 to provide a fluid reservoir or chamber therebetween. Suitable packing, such as 44 and 45, are provided between the shell 43 and the disk 40 and between the shell and the member 34, respectively, to prevent the entrance of liquid into the interior of the shell 43.

Disposed immediately adjacent and slidable upon the inner surface of the shell 11 is a cylindrical valve member 46 which is provided with openings 47. These openings 47 are adapted to be aligned with the openings 12 through the shell 11 when the valve member is in one position thereof, for example, when the valve member is at its extreme right-hand position as viewed in Fig. 3. The right-hand end of the valve member 46, as viewed in the drawings, is provided with an inwardly directed flange 48 having a threaded opening in which the inner end of an adjusting screw 49 is screwed. The outer end of the adjusting screw extends in sealing relationship through the members 14 and 16 and exteriorly of the latter. The outer portion of

the screw 49 is preferably of reduced diameter to provide a shoulder 50 which cooperates with the member 16 to prevent endwise movement of the screw to the right as viewed in Fig. 3. Exterioly of the member 16 the extending portion of the screw 49 is provided with a means for effecting rotation thereof which, in the illustrated embodiment, comprises a knob 51 pinned or otherwise secured to the screw, the said knob having a boss 52 which cooperates with the outer face of the member 14 to prevent displacement of the screw to the left, as viewed in Fig. 3. As shown in Fig. 4, the adjusting member or knob 51 is preferably provided with calibrations 53 which cooperate with a stationary pointer or indium member 54 mounted upon the member 16 to indicate the adjusted position of the valve member.

It will now be readily apparent that rotation of the knob 51 will cause the screw 49 to thread through the threaded portion of the flange 48, thus moving the cylindrical valve member 46 to dispose the openings 47 therein either in or out of alignment with the openings 12 in the sleeve 11. Hence, the extent of the movement of the valve member determines the size of the passageways provided through the valve member and the openings 12 and the adjusted position of the valve member is indicated by the position of the knob 53. Consequently, fluid, which is supplied through the bore 31 under pressure by any suitable means attached to the outer end of the member 18, flows through the bore 30 in the member 14 and through the openings 42 of the cylindrical boss 41, entering the passageway or reservoir between the shells 43 and 11 and thence flows through the openings 47 and 12 to the exterior of the shell 11, the rate of flow being controlled by the position of the valve member 46 which may be selectively positioned to completely terminate the flow, or to place the openings 47 and 12 in alignment, or at any intermediate position therebetween.

While a single adjusting screw and manually actuated knob have been shown for effecting adjustment of the valve member 46 it will be apparent that a plurality of adjusting screws may be provided at spaced points about the flange 48 which screws are actuated simultaneously for effecting adjustment of the valve member. For this purpose, each such adjusting screw may be provided with a pinion adjacent its outer end, the several pinions meshing with a single gear coaxial with the tubular member 18, a suitable means being provided to rotate one of the pinions or the single gear meshing therewith.

A strip-like member 55 is wound in a helical configuration having a relatively small pitch upon the outer surface of the cylindrical shell 11. This strip-like member 55 is preferably formed of stainless steel wire or other corrosive resistant metal which has been rolled or otherwise shaped to provide a substantially rectangular configuration with one side planar and the other side provided with a plurality of transversely extending, longitudinally spaced, protuberances or bosses, such as 56, see Fig. 7. In winding the strip or wire upon the cylinder, a plurality of pins, such as 57, are mounted on the surface of the cylinder adjacent one end thereof and extending radially outwardly therefrom a distance slightly greater than the height of the strip or wire, these pins being disposed in a helical path corresponding with the outer surface of the first convolution of the strip-like

member. The flat or planar side of the strip-like member 55 is then secured to the sides of the pins 57 by soldering, welding, or the like, and the strip is wound upon the drum with the protuberances 56 of one convolution abutting the planar face of the next convolution, the protuberances 56 being so spaced with respect to the circumference of the drum that the resulting spaces between adjacent protuberances are preferably in staggered relationship in adjacent convolutions. The strip-like member is wound over substantially the entire surface of the shell 11, which is to be utilized, with each convolution firmly engaging the adjacent convolutions and with the last convolution secured in place to pins 57 which are placed in a helical path adjacent the other end of the shell as in the case of the first convolution.

After the strip-like member has thus been wound upon the drum, and secured thereto, the outer surface of the resulting helix is ground, turned, or otherwise machined, to a true cylindrical surface and the outer ends of the pins 57 are likewise removed by the grinding so as to lie within this surface. The result is a perforate surface of true cylindrical form having a very great number of staggered elongated openings 56a of extremely narrow width therethrough which extend at substantially right angles to the axis of the cylinder and communicate with the longitudinal grooves 43 and the openings 42 in the shell 11. Hence, liquid under pressure may flow through the latter openings and grooves and be conducted to the surface of the cylinder through the openings 56a to provide a substantially uniform delivery of liquid to the said surface, the width of the openings 56a between the convolutions of the strip-like member being such that the liquid does not flow freely therethrough due to the capillary action unless at least slight pressure is applied thereto. The width of the strip-like member is also extremely small so that the fluid flowing outwardly from the several elongated openings 56a can merge on the outer surface of the cylinder to provide a substantially continuous film thereover. Strip-like members having a height of about .016 in., a thickness of approximately .005 in. and protuberances about .0015 in. high producing an overall thickness of about .0065 in. have proved satisfactory in practice, however, strip-like members of any suitable dimension may be used, depending upon the porosity of the surface desired.

A cylinder thus constructed may be used, without further preparation, to provide a uniform coating of a liquid upon web or sheet material passed over the surface of the helix, the liquid being transferred to the material by any known means but preferably being effected by means of an electrostatic or electromagnetic field. When employing an electrostatic field, one electrode thereof is mounted within the cylinder on the insulating bushing 39a surrounding the shaft 39. The other electrode is then supported adjacent the outer surface of the material to be coated so that the latter passes between the latter and the cylinder 10.

When the cylinder 10 is to be employed for printing, the outer surface of the helix formed by the wire or strip-like member 55 is provided with a skin or film of copper or other suitable metal which is preferably electrically deposited to form a continuous, even metal surface over the entire outer periphery of the wire or strip. In forming this thin layer or covering over the

helix, a powder, preferably copper powder moistened with water, is rubbed lengthwise of the cylinder to fill in the spaces or elongated openings 56a between the wire near the outer surface of the helix. These particles of powder, designated 58, bridge the said elongated openings, see Fig. 10, so that, when the cylinder is thus treated and placed in an electroplating bath, the copper covering or shell can easily bridge the gaps or elongated openings 56a between convolutions of the wire or strip without penetrating to the bottoms thereof. By way of example, it has been found that a suitable covering in the order of .002 in. in thickness can be accomplished in a period of from 30 minutes to 2 hours by grinding the shell during the plating operation. Preferably a high current density is employed during the initial plating operation to obtain a quick, heavy deposit, and the grinding can be carried on simultaneously with the plating operation or the plating and grinding can be alternated. During the final plating operation which is preferably conducted at a reduced current density to produce a fine grained deposit, the grinding wheel can be replaced by a polishing wheel or disk and a highly polished, smooth and even surface thus produced.

The cylinder is then removed from the electroplating bath and flushed clean with running water and may be further cleaned by dipping in a caustic potash solution or the like. If the potash solution be employed, it may then be neutralized by a short interval dip of the cylinder in a weak acid solution after which the cylinder is again flushed with running water.

The copper surface of the cylinder is now provided with a light-sensitive coating which may be a colloid or preferably a cold top enamel, which is well known in the industry. After this light sensitive coating is applied and dried, a photographic film, which is a negative image of the material which is to be printed is applied to the surface and the composite is then exposed to light. Where the cylinder is of considerable length so that a plurality of images may be applied thereto, the exposure to the light may be made simultaneously after all of the negatives have been applied thereto, or it may be made progressively for the particular portion corresponding with a given negative. After all the images have thus been exposed, the negative or negatives is or are removed and the cylinder is rotated in a suitable developing solution after which the cylinder is flushed with running water and then immediately dried. The cylinder will now show the exposed copper shell in all the non-printing areas, the image to be printed being represented by the light-hardened surfaces of the colloid or enamel material.

The image, or printing surfaces, after drying, are prepared with suitable resist, such as a greasy etching ink and powder, in order that the cylinder surface may be etched to remove the exposed non-printing portions of the copper shell. This etch may be effected by a suitable iron chloride bath in which the cylinder is placed for an interval of, say, from 15 to 20 minutes after which the cylinder may be placed in an electroplating bath and the current thereof reversed so that the balance of the exposed portions of the copper shell is removed or stripped by electrolytic action with the result that all of the wire or strip 55 representing the open spaces, or non-printing portions, in the image is exposed. Likewise any loose particles of the copper powder

58 left between the strands of the wire or strip 55 in these open spaces are removed by the electrolytic action. As a result, the metallic copper coating remains adhering to the surface of the helix only under the light-hardened image portions 59, see Fig. 8. After washing the cylinder, the light-hardened material on this remaining copper surface or surfaces is removed in any well-known manner and the non-printing areas, represented by the exposed wire or strip portions, are again coated with a desensitizing etch and then with a gelatinous or equivalent type coating which is light-sensitive. This latter coating is next light-hardened to about 60% of its hardness, thus providing a porous and relatively hard surface in the non-image areas 60.

A cylinder of this type may then be employed for printing in accordance with the offset or similar methods of printing. For this purpose, water or other suitable liquid under pressure is applied to the reservoir or chamber between the shells 43 and 11 and this liquid then travels through the openings 47 and 12 to the openings represented by the elongated slots 56a between the convolutions of the helix. The liquid below the areas covered by the image portions 59 cannot penetrate to the surface due to the copper shell that remains over these portions. The water below the non-image areas, such as 60, will, however, pass by capillary action through the pores of gelatinous coating in these areas, thus moistening the surface of the coating. Hence, when the cylinder is put in the press and greasy ink rollers applied, the ink will be transferred to the cylinder only where the image portion or portions exist. The moistened gelatinous or colloid surfaces such as 60 will repel the ink and hence will not be inked by the ink rollers.

This type of cylinder may also be employed for direct or relief printing by making the dimensions of the parts sufficiently great to withstand the forces produced. Consequently, it is no longer necessary to form separate electro-types or stereotypes as has been done heretofore. Moreover, in utilization of liquid expulsion from within the cylinder, as above described for either relief or offset printing, longer life images will be secured from the gelatin or non-image surfaces because water will moisten the small spaces between the fine grains thereof and keep them moist so that the ink will be repelled, which is not the case when the conventional water roller system is used for rolling water over the surface of the gelatin portions. Moreover, by the elimination of the necessity for a water roller to moisten the gelatinous non-image areas, sharper, more clearly defined, prints are obtained because the moisture is supplied from within and hence only the gelatinous material is thus moistened, whereas a conventional water roller, acting upon the outer surface of the gelatin, tends to also moisten the adjacent edges of the image areas thus preventing proper pick-up of ink from the ink rollers at such points, with resulting blurring of the print.

If the novel printing cylinder is to be employed for printing in accordance with gravure methods or by electronographic methods, the cylinder is prepared as above described up to the points at which the photographic image is produced thereon. Now, however, the photographic film employed is a positive transparency rather than a negative so that when the transparency is printed upon the sensitized surface of the cylinder, the light-hardening action will affect all of the non-

printing areas, such as 61, as shown in Fig. 9, while the printing areas, such as 62, will not be light-hardened. Hence, upon developing and washing, the material over the image areas 62 will be removed and expose the copper shell thereunder. The above steps of removing the exposed copper are then repeated as before described and the exposed portions of the wire or strip 55 are thoroughly cleaned and the light-hardened material over the remaining copper areas may be removed. The exposed portions of the wire 55 are, however, not provided with a gelatinous coating but are left exposed.

The cylinder thus prepared is then supplied with an ink or dye solution which is introduced through the bores 31 and 30 to the cylindrical reservoir or chamber between the cylindrical portions of the shells 43 and 11. This ink or dye then flows through the openings 47, 12, the grooves 13, and the elongated openings 56a in the wire or strip covering in the printing areas 62 which have been left exposed. The ink or dye does not, however, come through the non-image areas since the latter are covered by the portions of the copper shell which was not etched away. This ink or dye in the image areas 62 may then be transferred to the print-receiving material in the usual manner of gravure presses or the like.

A cylinder of the type just described is especially useful when printing in accordance with the electronographic method which employs electrostatic or magnetic fields of force to effect transfer of the ink or dye, from the printing areas such as 62, without pressure between the printing cylinder and the print-receiving material. When employing this type of printing, the cylinder 10 is preferably provided with a suitable electrode which, as stated above, may be mounted within the cylinder upon the insulated bushing carried by the shaft 39. A cooperating outer electrode is then provided adjacent the outer surface of the cylinder at the point or area where printing is to occur, the paper or other print-receiving material running between the surface of the cylinder and the outer electrode, as is now well known in this type of printing.

The cylinders constructed in accordance with this invention may be readily disassembled for purposes of cleaning as will be readily apparent from the previously described construction. If it be desired to screen the liquid before it passes through the minute openings 56a between the convolutions of the strip or wires 55 in order to prevent particles of solid material which may be present in certain inks or dyes from lodging in the passageways, a cylindrical screen 63 of fine mesh may be provided between the shell 11 and the valve member 46 as shown in Fig. 5. This screen also provides a means for further restricting the flow of fluid through the openings, such as 47 and 12, for any given setting of the valve member, thereby giving a better control of the flow for certain types of liquid. This wire screen 63 may be carried either by the inner surface of the shell 11 or by the outer surface of the valve member 46, but is preferably fixed to the latter to move therewith.

The strip-like material which is wound circumferentially about the cylindrical shell 11 may be formed in a variety of different manners. For example, as shown in Fig. 11, this material may take the form of two separate strips wound side-by-side on the shell 11 so that the convolutions of each strip alternate. Thus, one strip, such as

64, may be substantially rectangular in cross section with no protuberances while the other strip 65, may also be substantially rectangular in cross section but this strip is provided with spaced protuberances such as 66 and 67 on both sides. While the protuberances 66 and 67 have been shown as opposite each other it will be apparent that they may be staggered with respect to each other if desired. Moreover, the convolutions of either the strip 55 or the strips 64 and 65 may be made as separate rings and sleeved upon the shell.

It will be understood that when use of a given image on the printing cylinder has been completed, the image may be readily removed by simply placing the cylinder in an electroplating bath and reversing the current. This or any other suitable expedient removes the portions of the copper shell which represented the matter being printed. The helix is then cleaned and a new image provided thereon. Thus a cylinder which has been used for offset printing may be subsequently easily prepared for printing in gravure or electronographically, or conversely. Moreover, as mentioned above, by simply employing a cylinder as herein disclosed with no covering on the helix, a liquid supplied to the cylinder may be uniformly coated upon a material passed over the surface of the helix.

Various other modifications and adaptations will occur to those skilled in the art after having the advantage of this disclosure. Therefore, the invention is not to be considered as limited to the specific details of apparatus and steps of procedure herein illustrated and described, it being understood that the specific disclosures are only indicative of the present preferred embodiments of the invention and are not to be considered as limitation of the invention.

Having thus described my invention, I claim:

1. A cylinder adapted for use in printing or coating a material comprising, a perforated cylindrical shell with closed ends, strip material wound circumferentially around the outer cylindrical surface of said shell, the said strip material having portions thereof provided with transversely extending protuberances and adjacent convolutions of the strip material abutting each other thereby providing a plurality of elongated relatively narrow openings intermediate each convolution in communication with the perforations of said shell, an imperforate cylindrical member of lesser diameter than said shell supported interiorly of the latter substantially coaxially thereof thereby providing an annular liquid chamber intermediate said member and shell, and means to conduct liquid into said chamber, the said liquid penetrating to the surface of the wound material through the said narrow openings therein.

2. A cylinder as defined in claim 1 and further comprising a cylindrical valve member cooperating with the said perforations in said cylindrical shell for controlling the flow of fluid therethrough, and means for adjusting said valve member.

3. A cylinder as defined in claim 2 and further comprising a cylindrical screen positioned between said shell and said valve member.

4. A cylinder adapted for use in printing or coating a material comprising, a cylindrical shell with closed ends and having a plurality of perforations through the cylindrical side wall thereof with certain of said perforations being interconnected by grooves in the outer surface of

the side wall, an elongated strip of material having transversely extending protuberances spaced therealong, the said strip being wound circumferentially around the outer surface of the side wall of said shell with the plane of said strip substantially perpendicular to the surface of said shell, adjacent convolutions of said strip being in engagement with the protuberances in any one convolution engaging the adjacent convolution intermediate the regions of the protuberances on the latter convolution thereby providing a plurality of elongated relatively narrow openings intermediate each convolution of the strip in communication with the said grooves and perforations, means at the ends of said cylinder for rotatably supporting the latter, a second cylindrical shell having closed ends and an impervious side wall disposed within the first-mentioned shell, the diameter of said second shell being less than that of said first shell thereby providing an annular chamber for liquid therebetween, and means for conducting a liquid into said annular chamber through an end of the printing cylinder thereby providing a body of liquid within the first-mentioned cylindrical shell which penetrates to the outer surface of said wound strip through the narrow openings between the convolutions thereof.

5. A cylinder as defined in claim 4 and further comprising means to control the flow of fluid from the said annular chamber through the perforations in the side wall of the first-mentioned cylindrical shell.

6. A cylinder as defined in claim 5 and in which the means for controlling the flow of liquid through the perforations of said first-mentioned cylindrical shell comprises a cylindrical valve member slidably mounted within the said first shell and cooperating with the said perforations, and means for adjusting said valve member.

7. A cylinder as defined in claim 6 and further comprising a cylindrical screen positioned between said shell and said valve member.

8. A printing cylinder comprising, a perforate cylindrical shell, an elongated strip of material wound circumferentially around the outer surface of said shell, the said strip having transversely extending protuberances longitudinally spaced along substantially the entire length thereof and the adjacent convolutions of said wound strip being in engagement thereby providing a plurality of elongated relatively narrow openings intermediate each convolution in communication with the perforations of said shell, an imperforate member having a diameter less than that of said shell supported interiorly of the latter substantially coaxially thereof thereby providing an annular liquid chamber intermediate said member and shell, and an impervious material on a portion of the exterior of said wound strip, the said impervious material having a configuration representative of the matter to be reproduced by printing and closing the said elongated openings thereunder, whereby liquid from the said liquid chamber can penetrate to the surface of said wound strip only in the areas thereof which are not covered by the said impervious material.

9. A printing cylinder comprising, a perforate cylindrical shell, elongated strip material wound circumferentially around the outer surface of said shell, the said material having transversely extending longitudinally spaced protuberances and the adjacent convolutions of said wound material being in engagement thereby providing a

plurality of elongated relatively narrow openings intermediate each convolution through which liquid may flow from the interior of said shell to the outer surface of the wound material, an imperforate member having a diameter less than that of said shell supported interiorly of the latter substantially coaxially thereof thereby providing an annular liquid chamber intermediate said member and shell, impervious material on the exterior of said wound material identical in configuration with the matter to be reproduced by printing and closing the said elongated openings thereunder, and a porous material disposed upon the said wound material within the spaces between the boundaries of the impervious material corresponding to the non-printing areas, whereby the surfaces of said non-printing areas are moistened by the penetration of liquid from the said annular liquid chamber within said shell through the said elongated openings and the porous material thereover thereby preventing adherence of a printing substance to the surfaces of said non-printing areas.

10. A printing cylinder comprising, a perforate cylindrical shell, an elongated strip of material having one side substantially planar and the other side provided with transversely extending protuberances spaced longitudinally along substantially the entire length of the strip, the said strip being wound helically upon the outer surface of said shell with the said planar surface substantially perpendicular to the surface of the shell and the adjacent convolutions of the said strip in engagement, thereby providing a plurality of elongated relatively narrow openings intermediate each convolution through which liquid may flow from the interior of said shell to the outer surface of the helix, an imperforate member having a diameter less than that of said shell supported interiorly of the latter substantially coaxially thereof thereby providing an annular liquid chamber intermediate said member and shell, impervious material on the exterior of said helix identical in configuration with the matter to be reproduced by printing and closing the said elongated openings thereunder, and a porous material disposed upon said helix within the spaces between the boundaries of the impervious material corresponding to the non-printing areas, whereby the surfaces of said non-printing areas are moistened by the penetration of liquid from the said annular chamber within said shell through the said elongated openings and the porous material thereover thereby preventing the adherence of a printing substance to the surfaces of said non-printing areas.

11. The method of constructing a cylinder adapted for use in printing or coating a material comprising the steps of, providing a cylindrical shell, forming a large number of spaced relatively small-dimensioned openings through the cylindrical side wall of the shell, forming a plurality of spaced grooves in the outer surface of said shell with each groove interconnecting certain of the said openings, providing an elongated strip of material having transversely extending longitudinally spaced protuberances therealong, securing one end of said strip to the outer surface of the side wall of said shell adjacent an end of the latter, winding the said strip of material circumferentially about the outer surface of the side wall of said shell with the plane of the said strip of material substantially perpendicular to the surface of the shell and with the protuberances on any one convolution engaging planar portions on the adjacent convolution thereby forming a plurality of elongated relatively narrow passageways for liquid through the wound strip and in communication with the said openings in the side wall of the shell, securing the other end of the strip of material to said shell adjacent the other end of the latter, removing a portion of the outer surface of the wound strip to provide a smooth cylindrical surface, providing a relatively thin shell of impervious material over the entire surface of the wound strip, and removing portions of the said impervious shell so that the remaining portions thereof have a configuration representative of the matter to be reproduced by printing, whereby liquid from within the said cylindrical shell can penetrate therefrom and through the elongated openings in the wound strip only in the areas from which the impervious shell has been removed.

12. The method as defined in claim 13 and wherein the said impervious material is electro-

portions on the adjacent convolution thereby forming a plurality of elongated relatively narrow passageways for liquid through the wound strip and in communication with the said openings and grooves in the side wall of the shell, securing the other end of the strip of material to said shell adjacent the other end of the latter, and then removing a portion of the outer surface of the wound strip in a manner providing a smooth cylindrical surface.

13. The method of constructing a printing cylinder comprising the steps of, providing a shell having a perforate cylindrical side wall, providing strip material having portions thereof provided with transversely extending protuberances, securing portions of the said strip material to said shell adjacent an end of the latter, winding the said strip material circumferentially about the outer surface of the side wall of the shell with adjacent convolutions of the strip material in abutment thereby forming a plurality of elongated relatively narrow openings intermediate the convolutions in communication with the perforations of said shell, securing the strip material to said shell adjacent the other end of the latter, providing a relatively thin shell of impervious material over the entire surface of the wound strip material, and removing portions of the said impervious shell so that the remaining portions thereof have a configuration representative of the matter to be reproduced by printing, whereby liquid from within the said cylindrical shell can penetrate therefrom and through the elongated openings in the wound strip material only in the areas from which the impervious shell has been removed.

14. The method of constructing a printing cylinder comprising the steps of, providing a cylindrical shell, forming a large number of spaced relatively small-dimensioned openings through the side wall of the shell, forming a plurality of spaced grooves in the outer surface of said shell with each groove interconnecting certain of the said openings, providing an elongated strip of material having transversely extending longitudinally spaced protuberances therealong, securing one end of said strip to the outer surface of the side wall of said shell adjacent an end of the latter, winding the said strip of material circumferentially about the outer surface of side wall of the shell with the plane of the said strip of material substantially perpendicular to the surface of the shell and with the protuberances on any one convolution engaging planar portions on the adjacent convolution thereby forming a plurality of elongated relatively narrow passageways for liquid through the wound strip and in communication with the said openings in the side wall of the shell, securing the other end of the strip of material to said shell adjacent the other end of the latter, removing a portion of the outer surface of the wound strip to provide a smooth cylindrical surface, providing a relatively thin shell of impervious material over the entire surface of the wound strip, and removing portions of the said impervious shell so that the remaining portions thereof have a configuration representative of the matter to be reproduced by printing, whereby liquid from within the said cylindrical shell can penetrate therefrom and through the elongated openings in the wound strip only in the areas from which the impervious shell has been removed.

plated upon said wound strip and ground and polished to produce a smooth, thin shell thereon.

15. The method as defined in claim 13 and wherein the said impervious material is electroplated upon said wound strip, initially at a high current density to produce a quick, heavy deposit, and subsequently at a reduced current density to produce a fine grained deposit.

16. The method as defined in claim 13 and wherein the said impervious material is electroplated upon said wound strip, initially at a high current density to produce a quick, heavy deposit, and subsequently at a reduced current density to produce a fine grained deposit, and wherein the deposits is ground during the initial plating operation and polished during the final plating operation to obtain a smooth, even surface.

17. The method as defined in claim 13 and wherein the said impervious material is electroplated upon said wound strip and is thereafter provided with a light sensitive substance upon which substance the matter to be printed by said cylinder is photographically reproduced thereby providing light-hardened areas and non-light hardened areas of said substance; the said non-light-hardened areas of said substance then being removed so that portions of the said electroplated shell are exposed and other portions are covered by the light-hardened substance, the said portions of the impervious shell which are removed being the portions thereof which are thus exposed.

18. The method as defined in claim 13 and further comprising the step of applying porous material over said wound strip in the areas from which the said impervious shell has been removed.

19. The method of constructing a printing cylinder comprising the steps of, providing a shell having a perforate cylindrical side wall, providing strip material having portions thereof provided with transversely extending protuberances, securing portions of the said strip material to said shell adjacent an end of the latter, winding the said strip material circumferentially about the outer surface of the side wall of the shell with adjacent convolutions of the strip material in abutment thereby forming a plurality of elongated relatively narrow openings intermediate the convolutions in communication with the perforations of said shell, securing the strip material to said shell adjacent the other end of the latter, filling the outer ends of the elongated openings in the wound strip material with finely divided material, electroplating a relatively thin shell over the entire outer surface of the wound material, and then removing portions of said thin shell and the finely divided material under the said removed portions in a manner such that the remaining portions of the said thin shell have a configuration representative of the matter to be reproduced by printing with the cylinder, whereby liquid within the cylinder can penetrate therefrom and through the elongated openings in the wound material only in the areas from which the said thin shell has been removed.

20. The method of constructing a printing cylinder comprising the steps of, providing a

cylindrical shell having a perforate side wall, providing an elongated strip of material having transversely extending longitudinally spaced protuberances therealong, securing one end of said strip to the outer surface of the side wall of said shell adjacent an end of the latter, winding the said strip of material circumferentially about the outer surface of the side wall of said shell with the plane of the said strip of material substantially perpendicular with the surface of the shell and with the protuberances on any one convolution engaging planar portions on the adjacent convolution thereby forming a plurality of elongated relatively narrow passageways for liquid through the wound strip and in communication with the perforations in the side wall of the shell, securing the other end of the strip of material to said shell adjacent the other end of the latter, removing a portion of the outer surface of said wound strip to provide a smooth cylindrical surface, filling the outer ends of the said relatively narrow passageways in the said wound strip with finely divided material, electroplating a relatively thin shell over the entire outer surface of the wound strip, and then removing portions of said thin shell and the finely divided material under the said removed portions in a manner such that the remaining portions of the said thin shell have a configuration representative of the matter to be reproduced by printing with the cylinder, whereby liquid within the cylinder can penetrate therefrom and through the elongated openings in the wound strip only in the areas from which the said thin shell has been removed.

21. In the method of constructing a printing cylinder, the steps of providing a cylindrical shell having a perforate side wall, providing the exterior side wall of said shell with a metallic material having a large number of small dimension openings therein, filling the outer ends of said openings with finely divided material, electroplating a relatively thin shell of metal over the outer surface of said material and said particles whereby the said thin shell bridges the said perforations without materially penetrating therein, and then removing portions of said thin electroplated shell and the said particle thereunder in accordance with the configuration of the desired image, whereby the perforations under the removed portions are available for conducting a liquid from the interior of said cylindrical shell.

WILLIAM C. HUEBNER.
